UNITED STATES PATENT OFFICE

ROBERT E. MCKIBBEN, OF PITTSBURGH, PENNSYLVANIA

ICE-CREAM HOLDER OR CONE

Application filed January 18, 1928. Serial No. 247,713.

My present invention has reference to a holder or container for ice cream or other sticky and dissoluble confections and my object is the provision of a holder for this purpose which is in the nature of a pastry or of any other edible material, and which includes a body that receives the cream or confection therein or thereon and a cap which has a frictional engagement with the body 5 to establish an air-tight joint therebetween, the said joint also preventing the accidental disassociation of the cap from the body so that the pastry may be conveyed or conveniently carried for an indefinite period and 10 retained without danger of deterioration.

To the attainment of the foregoing the invention consists in the improvement as hereinafter described and definitely claimed.

In the drawings:

20 Figure 1 is a perspective view of one form of the improvement, the cap being elevated above the body.

Figure 2 is a sectional view through the improvement, the cap being arranged on the 25 body.

Figure 3 is a view similar to Figure 1, but illustrating a slight modification.

Figure 4 is a sectional view through the embodiment of the invention disclosed by 30 Figure 2, the cap being arranged on the body.

In Figures 1 and 2 of the drawings, the body 1 of the improvement is cone-shaped, and the hollow body is designed to receive 35 therein ice cream or other sticky confection, which is liable to melt when exposed to the air. Below the open mouth the body 1 is provided with a continuous enlargement in the nature of a rim 2, and the outer edge of 40 the rim is preferably rounded.

The numeral 3 designates the hollow dome-shaped cap for the body. This cap has at its mouth, an outwardly extending continuous ring flange 4 which is designed for 45 frictional engagement with the annular extension 5 of the body 1 that projects beyond the rim 2. The cap has its body portion rounded outwardly to its juncture with the ring flange 4. This affords what may be 50 termed a flared mouth between this portion

of the cap and the body 1 adjacent thereto and serves as a passage for the compressed ice cream and the moisture or vapor emanating therefrom when the cream is compressed on the base by the pressure of the cap thereagainst so that such moisture or vapor will enter the joint between the body 1 and the ring flange of the cap to effectively seal these elements together. There is a frictional engagement between the flange 4 of the cap 3 and the part 5 of the body 1 when the cap is arranged on the body, and when so arranged the outer edge of the flange 4 will rest on and firmly contact with the outer shoulder provided by the rim 2. The improvement is in 65 the nature of some suitable edible pastry, and the body 1 provides a holder for ice cream or like confections while the cap 3 effectively seals the body for preventing the confection from deterioration.

In Figures 3 and 4, the cap 3' is similar to that previously described but the body 1' is in the nature of a disc having a lower rim portion 2' and an upper annular portion 5' that receive the annular flange 4' of the cap 3' 75 thereon. As disclosed by Figure 4 ice cream or other confections are arranged upon the flat top of the body 1' and when the cap 3' is arranged thereover this confection is effectively protected from the atmosphere and 80 may be conveniently carried from place to place. Both the body 1' and the cap 3' may be of edible and preferably sweetened material, but obviously may be of other material.

It is to be noted that incident to the sticky 85 consistency of the contents of the container any vapor or moisture emanating therefrom will, in its attempt to find a passage between the body and cap, cause the joint between these elements to be treated to such adhesive 90 substance and thereby more positively hermetically sealing the joint.

In practice the ice cream is scooped in the usual manner and is placed either in the cap or on the top of the body 1. The cap is then 95 arranged over the body and the said cap will compress the ice cream between the interior of the cap and the body, forcing the moisture and vapor from the ice cream into the joint between the ring flange of the cap and the 100

body and thereby effectively sealing the cap to the body. The container is eaten with the cream, or in other words, is not separated in order to remove the ice cream therefrom after the cream has been arranged therein. 5 The improvement obviates the expense on the part of the retailer in packing the cream in the ordinary manner and the cream as well as the container therefor will be preserved for a great length of time, as a matter-of-fact, a number of containers which are filled with ice cream may be placed in a bag for delivery and, as stated, will remain in practically the same condition as when packed 10 after the buyer has conveyed his package to his home or for a considerable distance away from the place where the cream was purchased. 15

Having described the invention, I claim:

20 A holder for ice cream of edible material, comprising a body having a round top and a continuous ring enlargement below the top, and a hollow dome-shaped cap for the body, having its lower edge rounded outwardly and formed with a depending ring flange which is designed for frictional engagement with the mouth of the body and likewise designed to rest upon the flange of the body, and said body and cap designed to receive 25 therebetween a scoop of ice cream and to compress the cream between the body and cap to cause the moisture and vapor therefrom to enter the joint between the body and cap and hermetically seal the cap to the body. 30

35 In testimony whereof I affix my signature.
ROBERT E. McKIBBEN.
